UNITED STATES PATENT OFFICE.

CHARLES R. STORZ, OF NEW YORK, N. Y.

SCISSORS-TOOL PIVOT.

Application filed July 21, 1922. Serial No. 576,621.

To all whom it may concern:

Be it known that I, CHARLES R. STORZ, a citizen of the United States, residing at New York, in the county of New York and 5 State of New York, have invented certain new and useful Improvements in Scissors-Tool Pivots; and I do hereby declare the following to be a full, clear, and exact description of the same, reference being had to the 10 accompanying drawings, forming part of this specification.

This invention relates to a pivot for use with such tools as have two cooperating arms and also relates to the tools themselves, par- 15 ticularly to scissors of the usual types.

In practically all scissors the pivot is a screw which has a threaded engagement with one of the blades and has at its free end a cylindrical journal surmounted by a head 20 kerfed in the usual manner for the reception of a screw driver. Pivots of this nature are adjusted by tightening the screw until the proper friction between the blades is secured and then the threaded portion in the 25 screw is locked against rotation with the blade by deforming the screw by punching, or by welding, or in some other manner. The scissors then have a pivot permanently secured to one of the blades and have the other blade pivotally mounted on the headed 30 end of the screw so that the head of the screw and the blade mounted thereon turn with respect to each other as the scissors are operated and unless the threaded portion of 35 the pivot is secured to the other blade in some manner the pivot soon loosens. On the other hand if the pivot is permanently secured to the under blade the scissors soon become loose due to the wear of the parts 40 and frequently it is quite impossible to tighten them.

It is the object of the present invention to eliminate these disadvantages of scissors pivots and to provide a pivot which will have no tendency to unloosen and one in which the head of the adjusting screw will be immovable with respect to the proximate blade during the cutting operation. This 45 adjusting screw has a threaded engagement with the pivot journal while the lower blade turns freely with respect to the upper blade, the adjusting screw, and the pivot journal; the latter three parts moving as a unit in the normal cutting operation.

50 In the drawings,—

Figure 1 is a bottom plan view of a pair of scissors embodying the present invention, the head of the adjusting screw being considered as being on the top face of the 55 scissors.

Fig. 2 is a transverse cross section through the pivot.

Fig. 3 is a top plan view of the pivot member or bushing.

Fig. 4 is an elevation thereof.

The scissors illustrated in the drawings are of the detachable blade type which type of scissors is rapidly displacing the older type in which the arms and cutter blades are integral. The detachable blades 70 form no part of the present invention, however, except in combination and the pivot is equally useful on scissors of the older type and other tools employing a pair of pivoted members or arms.

The cutter blade carrying arms 10 and 11 hereafter called the upper and the lower arm for convenience of description, each carry a thin steel detachable cutting blade 12 adapted to be secured to the arms 10 and 11 by fastenings 14 of the cling blade type so that a dull blade may be removed with little or no difficulty and may be replaced by a sharp one in the same manner as a safety razor blade is removed. The 80 arms 10 and 11 each carry a handle 15 of the usual configuration so that when closed the scissors closely resembles the older type.

The pivot of the present invention is materially different, however from the ordinary pivot and consists of two cooperating members, one an ordinary headed screw 16 which fits within the internally threaded axial opening 17 through the bushing 18, the head of the screw being 90 of such size as to overlie the upper face of the arm 10. If desired the screw head 16 may be countersunk in the arm 10 in accordance with quite usual practice but the form illustrated is deemed preferable.

The bushing 18 is generally cylindrical but has two plane side faces 20 extending slightly more than half way down the bushing leaving a true cylindrical portion 21 which forms a pivot journal, this journal portion merging into the circular head 22 adapted to fit into the countersunk portion 23 in the lower arm 11. It is obvious that the head 22 need not be circular and also need not be received within a countersunk 105 110

portion but may overlie the arm 11 in the same manner as the head of the screw 16 in the preferred form overlies the arm 10, the purpose of the heads being to hold the two arms assembled in pivotal relation.

The bushing 18 is slotted as at 25 for a portion of its length in order to more securely hold the adjusting screw 16 in desired position. The portions on either side 10 of the slot or slit 25 may be resilient to embrace the screw or if desired the non-circular orifice 27 in the arm 10 may be slightly tapered as shown in Fig. 2. The hold 27 is 15 preferably the exact shape of the cross section of the bushing through the two plane faces 20 and should form a snug fit therewith. The opening 30 in the arm 11 is cylindrical and forms a bearing for the journal 22.

20 It is preferred that the shoulder 31 formed by the two plane faces 20 shall be slightly beneath the two cutting blades 12 and that the pivot holes in these blades shall be circular this being slightly more convenient 25 in the process of manufacture, although obviously the upper blade 12 might have a pivot hole which would correspond to the hole 27, and the shoulder 31 would then be placed just beneath the plane of the cooperating faces of the two cutter blades.

To assemble the device the bushing 18 is inserted in the two-diameter bore of the lower arm 11 and the bushing is then pushed into the non-circular hole 27 until nearly 35 the correct amount of friction is secured. The screw 16 is now inserted in the central threaded opening of the bushing and is tightened until the exact amount of friction has been obtained and the scissors are then 40 ready for use. Since the bushing 18 is

locked to turn with the arm 10 and since the adjusting screw 16 also turns with this blade it is obvious that there is no tendency of any kind for the screw to unloosen and that the bushing is freely rotatable within 45 the lower arm 11.

It frequently happens with the older types of scissors where the screw pivot is not deformed that the scissors will work nicely until they are oiled, but oiling will cause 50 the pivot to loosen. In the present construction this disadvantage does not obtain since there is no relative movement between the screw and the bushing or the arm 10. It should also be obvious that an extreme 55 nicety of adjustment is possible as the threads on the screw and bushing may be very shallow. As the bearings wear the adjustment may be maintained by a very slight turning of the screw with a screw driver from time 60 to time.

What I claim is:

In a scissor tool, a pair of arms, one of said arms having a circular opening therein and the other a non-circular tapered opening, an internally threaded bushing having a circular portion fitting the circular opening in one arm and having a non-circular portion fitting said non-circular tapered opening, the opposite sides of said non-circular portion of the bushing being flat and extending substantially parallel to each other, the non-circular portion of the bushing between said flat faces being slotted and semi-circular with the arcs formed by its semi-circular surfaces struck on the same radius as the circular portion of the bushing, and a headed screw secured in said bushing.

CHARLES R. STORZ.
